UNITED STATES PATENT OFFICE.

THOMAS T. HUTCHINSON, OF NEWARK, NEW JERSEY.

CIGARETTE.

No. 922,481.

Specification of Letters Patent.

Patented May 25, 1909.

Application filed February 3, 1909. Serial No. 475,736.

To all whom it may concern:

Be it known that I, THOMAS T. HUTCHINSON, of the city of Newark, in the county of Essex and State of New Jersey, have invented certain new and useful Improvements in Cigarettes, of which the following is a specification, reference being had to the accompanying drawings, forming a part hereof.

The invention relates to improvements in what are known as "Autolite" or self-lighting cigarettes and particularly to the igniting tip upon the end of such cigarettes. One practical objection to the use of such a tip is that the fumes generated thereby are liable 15 to permeate the tobacco.

In accordance with the present invention, the cigarette is provided with recesses, holes or perforations in the tip itself and also just back of the tip in the paper of the cigarette if 20 desired.

The invention will be more fully described in connection with the accompanying drawing in which the figure is a view in perspective of the cigarette in which the improvements have been embodied.

As shown in the drawing, the igniting tip *g* is provided with a perforation *o* near the center of the tip, which may or may not extend entirely through the same, and with perfora-

tions *n* just back of the tip in the paper of the cigarette, whereby the fumes formed by the burning of the tip may escape and may not therefore be liable to permeate the cigarette itself and to be drawn back into the mouth of the smoker. These perforations may obviously be formed in different ways and may be provided wholly in the tip or in the periphery of the cigarette, although it is preferable to form them both in the tip and in the periphery of the cigarette as illustrated. 30 35 40

I claim as my invention:

1. A cigarette having an ignition tip with a recess therein for the purpose specified.
2. A cigarette having an ignition tip and perforations just back of the tip for the purpose specified. 45
3. A cigarette having an ignition strip extending completely over the end of the cigarette, perforations around the cigarette just back of the tip, and a perforation near the center of the tip. 50

This specification signed and witnessed this 21st day of January, A. D., 1909.

THOS. T. HUTCHINSON.
